UNITED STATES PATENT OFFICE.

HARRY BUXTON HARTMAN AND FRANK E. HARTMAN, OF SCOTTDALE, PENNSYLVANIA, ASSIGNORS TO ELECTRIC WATER STERILIZER AND OZONE COMPANY, OF SCOTTDALE, PENNSYLVANIA, A CORPORATION OF PENNSYLVANIA.

DEHYDRATOR.

Application filed September 16, 1925. Serial No. 56,786.

This invention relates to dehydrators for supplying dry air to ozone apparatus for the purpose of increasing the output of ozone, and keeping its production constant.

5 A primary object of the invention is to provide a dehydrator of adequate capacity and which includes means for reactivating the dehydrating material without dismantling the apparatus and without loss 10 of time in operation. In that connection the invention contemplates reactivating or regenerating means that may be manually set in operation at the proper time and automatically cut out when the dehydrating medium is reactivated.

15 A further object of the invention is to provide a dehydrator of simple and practical construction which may be easily manufactured and assembled, and which is also susceptible of embodiment in multiple unit form.

With the above and other objects in view which will more readily appear as the nature of the invention is better understood, 25 the same consists in the novel construction, combination and arrangement of parts hereinafter more fully described, illustrated and claimed.

30 A preferred and practical embodiment of the invention is shown in the accompanying drawings, in which:

Figure 1 is a vertical sectional view of an apparatus illustrating the present improvements.

35 Figure 1^a is a detail view of the outlet connections for the dry air.

Figure 2 is a detail vertical sectional view taken on the line 2—2 of Figure 1.

40 Figure 3 is a detail horizontal sectional view taken on the line 3—3 of Figure 1, with heater shown in dotted lines.

Figure 4 is a detail elevation of a multiple unit apparatus embodying novel features of construction and arrangement.

45 Similar reference characters designate corresponding parts throughout the several figures of the drawings.

As will be observed from Figure 1 the present device includes in its organization a 50 hollow base member or air intake section 1 supported on the legs or equivalent members 2 and having the interior horizontal guideways 4 while the upper edge thereof is troughed as indicated at 5 thereby to receive

the cylinder 6 which provides the main wall 55 of a holder for the dehydrating material, as will presently appear. The cylinder 6 is provided with a dry air discharging section or cap 7 whose lower edge fits into the troughed or grooved portion 8 at the upper 60 edge of the cylinder 6. The base 1 and cap 7 are held together by means of the relatively long tie bolts 9, the said cap and base clamping therebetween the cylinder 6 to maintain the parts described in the relation set forth. 65

The air receiving base section 1 is open at one side as indicated at 10 in Figure 2 and the said opening may be covered by a removable door or hand-hole plate 11. Above the door 11 there is mounted a wiring 70 box 12 for housing the electrical connections for establishing contact between the outside power lines 13—13^a and the wires 14 of the heating element 15. This location of the box 12 permits of the free removal and replacement of the door 11 without interfering with the wiring connections to the heating element 15. The inside face of the door 11 also carries an offset flange 11^a lying in the same plane as the upper wall of the 75 guide 4. This heating element preferably comprises a ring 15 of fire-clay, porcelain or other materials having the heating wires 14 wound thereabout. The lower edge of said ring 15 rests upon the base plate 16 80 which is slidably mounted in the guides 4 previously referred to, but does not cover a series of openings 17 in the plate which are so arranged that air passing through the 85 same will be coursed over the heating elements 14 to pick up heat therefrom to reactivate the dehydrating material, as hereinafter more fully set forth.

The cylinder 6 which provides a reservoir or holder section for the porolyte or other 90 dehydrating material is preferably formed near its lower edge with an annular offset bead or rim 19 which supports a spider 20 having its upper side faced with a relatively fine meshed screen 21. This permits the 100 free entrance of air upwardly through the chamber or reservoir but holds the dehydrating material in place.

The bottom of the base 1 below the plate 16 is formed into an air inlet chamber "C" 105 by reason of the fact that the plate 16 having the openings 17 cooperates with the guideways 4 to partition off the lower portion of

the base so that the only way that air can escape therefrom is through the openings 17. In that connection it is important to observe, particularly from Figure 2, that the door 11 carries the inside offset flange 11^a to overlap the front edge of the plate 16 thereby forming in effect a continuation of the upper wall of the guide 4 so that no air will escape between the front edge of the plate and the inside face of the door. Thus, with this arrangement air must escape from the chamber C through the opening 17 and thereby effectively pick up heat from the wires 14 when the porolyte is to be dried or reactivated.

Air under pressure is supplied to the chamber "C" through the pipe line 22. This pipe line is fitted with an automatic valve 23, which is so designed as to open and bypass to atmosphere all excess air which is not permitted to pass out through pipe line 22 by reason of valve manipulations, as will be more clearly seen later.

If unit volume per minute of air is required for ozonizing, for activating the drying material ten units of volume of air will be required per minute, it is the function of the valve 23 to permit of the use of two distinct rates of flow from the one blower.

The motor 25 is connected by the wires 26 and 26^a with the terminals 27 and 27^a of a temperature protecting relay designated as R. Also the wires 13 and 13^a are connected with the terminals 28 and 28^a of a double pole-double reversing switch designated as S, whereby when the handle H of the switch is in the position shown in Figure 1 current may be supplied through the blades 29 of the two-blade switch controlled by the handle H thereby to connect said terminals 28 and 28^a with the wires 30 and 30^a of an automatic cut-out switch designated generally as A. This device A is of a more or less standard construction and is therefore only diagrammatically shown in Figure 1 and operates in conjunction with a thermostat T mounted within the cap 7 and connected with the automatic cut-out switch A by a suitable electrical connection T'. The thermostat T in Figure 1 is shown diagrammatically at the side of the cap instead of at the front to more conveniently show the circuits involved. The automatic switch A is supplied with electrical current from outside power lines P. Power from P may be supplied to the motor 25 and the heating wires 14 by placing the handle H of the switch S in the position shown in Figure 1. By reversing the handle H of the switch S as shown by the broken lines in Figure 1 power from P may be connected with the motor 25 and an ozone producing unit (not shown) connected with the wires P', thus severing the power connection with the heating wires 14.

The operation of the construction shown in Figures 1 to 3 inclusive is substantially as follows:

After the device is assembled, as shown in the figures above referred to, and the holder section, or container 6, is filled with porolyte or other drying medium D, the handle of the switch S is placed in the opposite position from that shown in solid lines in Figure 1. The handle of the three-way valve V is also so placed as to direct the air from the outlet 7^a of the holding section 6 to an ozone producing unit, connected with the dehydrator through the three-way valve V, the needle valve N and 80 the flow meter F. When the three-way valve V is in this position, the port of the three-way valve opening to the atmosphere is sealed. The switch S being in the position to energize the ozone producing unit through the lines P', and the motor 25, which operates the blower 24, air will be delivered by the blower 24 through the pipe 22 to the receiving chamber C, thence to the holder section 6 where it will be brought into intimate contact with the drying medium D, thus removing the aqueous vapor content from the air. The dried air will be subsequently delivered to the ozone producing unit through the three-way valve V, the needle valve N serving to regulate the quantity delivered to the ozonizer, and this quantity will be determined by the flow meter F. The entire capacity of the blower 24 will not be required for ozonation, in fact only ten 100 per cent of the capacity will be required. Due to the friction introduced by the needle valve N the excess air will be automatically exhausted by the by-pass relief valve 23, without having to pass through the dehydrator.

The effectiveness of the drying medium D will of course depend upon the temperature of the air supplied it, and the amount of water vapors which it contains. The dimensions of the holder section 6 should be so calculated as to effectively dry the air at the maximum humidity to be expected of the raw air, at its maximum temperature and fixed velocity. The capacity should be such as to permit of at least use for one week before the drying medium will require reactivation. When the drying medium becomes saturated it becomes necessary to activate it. This is accomplished by reversing the handle of the switch S, thus disconnecting the ozone producer from the power circuit and connecting the power with the heater wires 14, and at the same time maintaining the power connection to the motor 25. 120 The three-way valve V is then placed in the position which seals the dehydrator from the ozone producer and connects the dehydrator directly with the outside atmosphere through the three-way valve. When the three-way 130

valve is so placed the only resistance to the flow of the air, beyond the dehydrator, is that occasioned by its efflux from the port of the three-way valve. As this removes the 5 resistance to the flow of the air occasioned by the needle valve N, the back pressure will drop so that the automatic relief valve 23 will close, and direct the entire capacity of the blower through the dehydrator. The air 10 will pick up heat from the heater wires 14, which have been energized as before described, and will convey this heat to the drying medium in the holder section.

A large quantity of this heat will be utilized 15 in supplying the latent heat of vaporization to the water condensed in the drying material, so that the temperature of the efflux air will not be raised greatly above that of the surrounding air. This heat absorption 20 will continue until all of the water has been evaporated from the drying material and swept from the dehydrator by the air stream. When evaporation has been completed 25 the temperature of the efflux air will rise quickly thus supplying sufficient temperature to the thermostat T to cause it to open the solenoid circuit of the automatic switch A.

As the automatic switch A is operated by 30 a momentary contact push button station and hold-in tip, as shown by the wiring diagram of Figure 1, the thermostat is simply connected in series between the stop point of the push button and the solenoid of the 35 automatic switch A, therefore, on cooling the thermostat cannot close the automatic switch A, thus the power from P will remain off until the start button is manually depressed. The activating operation usually 40 requires from 6 to 10 hours, and an equivalent period of time is required for the drying material to cool, therefore, if the dehydrator is operated for a week and activation started 45 on Saturday night, by Monday morning the reactivation and cooling of the drying medium will be complete and by reversing the switch S and the three-way valve we can again continue the drying of air and the operation of the ozone producer.

50 A multiple unit type of apparatus is shown in Figure 4 of the drawings wherein the apparatus is shown in more or less diagrammatic form. This organization of parts may be used when continuous operation of the dehydrator is necessary, as where no periods of rest are available. In this form of apparatus, first one unit (F) and then the other unit (G) is alternately used for dehydrating purposes and alternately reactivating.

60 As will be observed from Figure 4 the automatic cut-out switch is designated generally as A', the two-pole switch designated as S'. Also the blower 24' and motor 25' are used in substantially the same way as previously described. However, the blower 24' is con-

nected with a pipe 35 which is in turn connected with a four-way valve 36 for controlling the passage of air to the unit F or the unit G through the pipe lines 37 and 38 respectively.

In the arrangement shown in Figure 4 the unit F is being operated to reactivate the dehydrating element. In this figure air under pressure from the blower passes through pipe line 35, valve 36 and line 37 to the bottom of the unit F, and then out through the connection 39 at the top of the unit and through the valve 40 to the atmosphere at 41. The valve 40 is located in a pipe line 42 which has a valve 43 at one end 75 for controlling communication between the unit G and the pipe 42 through the pipe connection 44, and as will also be observed from Figure 4 the line 42 is provided with a dry air take off connection 45.

When the unit F is being reactivated dry air is pulled through the unit G by suction 80 since the blower 24' is furnishing air under pressure to the unit F. That is made possible by placing a pump in the line 45, and the valve 36 being of such construction that when turned in the position shown in Figure 4 atmospheric air can be sucked into the pipe line 38 and thence through the unit G 85 before being discharged through the pipe line 44.

From the foregoing it will be apparent 90 that the present construction provides a simple and practical arrangement from a manufacturing and assembling standpoint, and also provides a construction which permits of readily reactivating the dehydrating element without taking the apparatus apart or otherwise rendering the dehydrator out of use when it is necessary to use the same 95 in connection with ozone apparatus.

With the position of the switch handle H shown in Figure 1 and the position of the valve V shown in Figure 1^a, it will be understood 100 that the dehydrating material D is being reactivated due to the fact that the blower 24 is supplying air to the heater 14-15 which is supplying hot air to the holder 6. The moisture laden air escaping through 7^a exhausts to the atmosphere to the valve V as shown in Figure 1^a. On the other hand when the switch handle H is thrown to the dotted line position the dehydrator is supplying dry air through the valve V to the ozonizer. Of course, under 110 these circumstances the three-way valve V is turned to place the line 7^a and the line containing the valve N in communication.

Without further description it is thought 115 that the features and advantages of the invention will be readily apparent to those skilled in the art, and it will of course be understood that changes in the form, proportion and minor details of construction 120 may be resorted to, without departing from 125 130

the spirit of the invention or scope of the appended claims.

We claim:—

1. In a dehydrator, a dehydrating material holder section, an air receiving section, a dry air discharging cap section, an electrical heating element in the air receiving section, means for manually cutting in said electrical heating element to reactivate the dehydrating material at predetermined periods, and means for automatically cutting out said heating element when the reactivating period has ended.
2. In a dehydrator, a dehydrating material holder section, an air receiving section, a dry air discharging section, means for supplying air under pressure to said air receiving section, electrical heating means in said air receiving section being normally inoperative, means for manually rendering said electrical heating means operative, and means for automatically rendering said heating means and air supplying means inoperative.
3. In a dehydrator, a dehydrating material holder section, an air receiving section, a dry air discharging section, means for supplying air under pressure to said air receiving section, electrical heating means in said air receiving section being normally inoperative, means for manually rendering said electrical heating means operative, and a thermostat in the cap section, and means automatically controlled by said thermostat for rendering the heating element inoperative and cutting off the supply of air to the air receiving section.
4. A dehydrator, a dehydrating material holder section, and air receiving section, a dry air discharging cap section, blower means for supplying air to said air receiving section, a motor for operating said blower, an electrical heating element in said air receiving section and normally inoperative, a thermostat in the cap section, a manually operated switch device for controlling the operation of the motor and the electrical heating element, and an automatic switch device controlled by said thermostat for automatically breaking the circuit to the motor and the heating element.
5. In a dehydrator, a dehydrating material holder section, an air receiving section and a dry air discharging section, means for supplying air to the air receiving section, and said latter section having a door at one side thereof, means for supporting a heating element in said air receiving chamber, an electrical heating element normally inoperative resting upon said supporting means, a manually controlled switch for supplying electrical current to said heating element, and means for automatically cutting off current from said heating element.
6. In a dehydrator, a dehydrating material holder section, an air receiving section and a dry air discharging section, means for supplying air to the air receiving section, said latter section having a guideway extending around three sides thereof, a door at the fourth side of said section, a support having openings adapted to slide in said guideway through the door, and an offset flange carried by the door and in line with the upper flange of the guideway to insure the passage of air through said openings in the plate, an electrical heating element mounted on said plate and disposed in the path of air currents passing through said openings in the plate, manual means for closing an electrical circuit to the heating element and automatic means for breaking the circuit to said heating element.
7. A reactivating dehydrator for use in connection with an ozone generator including in combination, a dehydrating material holder, means for supplying air to said holder, electrical heating means for said air before it passes to said holder, means for manually rendering said electrical heating means operative, and means for automatically rendering said electrical heating means inoperative due to differential temperature conditions in the holder after the dehydrating material has been reactivated.
8. A reactivating dehydrator for use in connection with ozone generators including in combination, a dehydrating material holder, an air supply line leading from said holder to the generator, a two-way valve in said air supply line for establishing communication between the holder and the generator or with the atmosphere, means for supplying air to said dehydrator holder and then through the valve to the supply pipe to furnish air for the production of ozone, electrical means for heating air furnished to said holder to reactivate the dehydrating material when the valve is turned to exhaust to the atmosphere, and means for automatically cutting off the supply of electrically heated air when the dehydrating material has been reactivated.

In testimony whereof we hereunto affix our signatures.
